COUPLING DEVICE

Arthur J. Bazeley, Cleveland, Ohio, assignor to
 National Malleable and Steel Castings Company,
 Cleveland, Ohio, a corporation of Ohio

Application December 1, 1931, Serial No. 578,239

11 Claims. (Cl. 213—127)

This invention relates to car couplers and particularly to those of the top-operated type. An object of the invention is the provision of an improved lock-lifter mechanism including a lock-to-the-lock which positively holds the lock not only against creeping to knuckle-unlocking position but also against movement to such position in response to sudden blows, especially those due to high-speed or impact coupling. A further object is to provide a lock lifter mechanism embodying an improved lock-to-the-lock having the characteristics above noted, and which at the same time may be readily operated manually to raise the lock to unlocking position. The invention is especially concerned with constructions of the general character disclosed in my copending application Serial No. 423,037, filed January 24, 1930. Other features of the invention will be hereinafter described and claimed.

20 In the accompanying drawing, Fig. 1 is a view partly in section and partly in elevation of a car coupler showing my improvements applied thereto. Fig. 2 is an enlarged detailed view showing the position of the lock lifting mechanism under conditions of impact coupling. Fig. 3 is a view similar to Fig. 1 but with the lifter raised and the lock in lock-set position. Figure 4 is a fragmentary detail view showing a modification of the invention.

30 Referring to the drawing, my invention is shown applied to a coupler of the standard D or E type, comprising a head A, knuckle B, knuckle-thrower C, and lock D. My improved lock lifter, in some respects similar to the construction described and claimed in my copending application above referred to, is designated generally at E and comprises an upper member 2 and a lower member 3, the latter having a hook-shaped lower portion engageable with a cross bar

40 or trunnion 4 which bridges a slot 5 in the lock. The upper member 2 projects through an opening 6 in the coupler head and has its lower end bifurcated to receive the upper end of the lower member 3, said members being connected by a pin 7 carried by the upper member and passing through a slot 8 in the lower member. The parts are so arranged that the weight of the upper member 2 causes the lower member 3 to break to the rear and when the lock is in lowermost position, forces the shoulder 9 at the top of the lower member under the ledge 10 in the coupler head, thus effecting a lock-to-the-lock.

The top portion of upper member 2 is shown as formed hollow and its rear wall is cut away as at 2' in order not to interfere with the free

action of the top of member 3. The upper lifter member 2, when in its normal or lowermost position wherein it rests upon the coupler head, is supported through projection 15 upon a top portion of the coupler head to the rear of the opening 6 but is not supported by the top surface of the coupler head forward of said opening. Through this arrangement, the occurrence of a sudden upward movement of the coupler imparts an upward impulse to projection 15 and causes the lower end of member 2 to tend to swing rearwardly during its upward movement; thereby, through the cooperation of pin 7 with the rear side 3' of slot 8 maintaining the shoulder 9 under the ledge 10. To facilitate the unlocking of the knuckle when the coupler is buffed rearwardly and a lifting force having a forward component is applied to the lifter member 2, as occurs with certain types of uncoupling mechanisms, the rear side of said member is provided with a shoulder 3' which, when the parts are in normal or locked position as shown in Fig. 1, lies slightly below the top of the shoulder 9. Now, if the coupler happens to be buffed back and the uncoupling rod applies an upward and forward force to member 2 the shoulder 3' is raised until it contacts with the shelf or ledge 10 and then as the pull on the member 2 continues, said shoulder 3' is cammed forwardly and out from under the ledge, by reason of the forward component of the pull, thus causing the lower end of the member 2 to swing forwardly and to carry with it the upper end of the member 3, whereby the shoulder 9 of the latter is withdrawn from under said ledge.

The features above mentioned are described in greater detail in my pending application hereinbefore referred to.

In carrying out my present invention, I mount in the hollow portion of member 2 a latch member 11 provided with a slot 12 through which passes a pin 13 secured to said member 2. Said pin 13 may conveniently be mounted in openings in the side walls of member 2 which openings constitute a core-supporting hole formed during the casting of said member. When the members 2 and 3 are in the position shown in Fig. 1, the latch member 11 drops down relative to the lower member 3 until its shoulder 14 lies immediately in front of the shoulder 22 of member 3, in the bifurcated portion of member 2. An inter-lock between the two members is thereby provided which prevents the shoulder 9 from being shifted out from under the ledge 10, even under extremely high speeds of impact coupling. The slot 12 is preferably

formed so that the member 11, in lock-to-the-lock position, will rest on the lower member 3, by reason of a slight clearance between the pin 13 and top of the slot. This clearance also allows 5 for variations in the parts and permits the latch member 11 to assume a lower position in the plug or member 2 as the lock wears and settles downwardly in the coupler head.

In this construction, the lock may be unlocked 10 by lifting member 2, whereupon said member will first be raised with respect to member 3, and as the pin 13 engages the top of the slot 12, will carry along with it member 11, withdrawing shoulder 14 from the path of shoulder 22 as 15 shoulder 9 is swung out from beneath the ledge 10 by pin 7; then both members 2 and 3 will be moved upwardly to operate the lock to lock-set or to knuckle-throw position; or, in other words, from the general position of the parts in Fig. 1 20 to their position in Fig. 3. In the latter view the lock is shown raised to lock-set position and lift member 2 is shown dropped down to the position where the lower end of its rear wall 2' rests on the upper end of member 3, the parts being capable 25 of remaining in this position until positively returned to locking position. It may be noted that the bottom end of the safety latch 11 also rests on top of the member 3, and does not hinder any pivotal movement between members 2 and 3.

30 In coupling cars, it is usually the case that the knuckle of one coupler is closed with the parts in locked position, while the next car has its knuckle open for engaging the first coupler. At unusually high speeds of impact coupling of cars in this manner, a severe blow may be imparted to 35 the first-named coupler. Due to this blow and the inertia of the parts of the lock-to-the-lock, these parts tend to swing forwardly in the coupler head into the general position shown in Fig. 2, and there is a tendency to throw the shoulder 9 entirely out from under the ledge 10. If this should happen, there would be nothing to prevent the lock and lock lift from rising. As there is 40 usually a small amount of droop to the coupler head, when the two couplers come together under a severe impact, they snap up to a horizontal position, and this sudden action tends to throw the lock up from its locking position. With the anti-creeping device momentarily out of commission, the lock might rise high enough to unlock 45 the knuckle. The direction in which the lock rises is indicated at Y in Fig. 2. This would be undesirable because under such conditions the cars would not be coupled. One of the principal 50 features of the present invention hence resides in the provision of simple and effective means for preventing possible unlocking of the lock under the conditions just described. For this purpose, it has been found that the construction already 55 described, including a latch such as member 11, is very satisfactory. As shown in Fig. 2, when the coupler is struck a hard blow in the direction of the arrow X and the inertia of the lifter members 2, 3 causes them to swing forward, the shoulder 9' on the lower member 3 engages the lower end 14 of the safety latch 11 before said member 3 can move forward sufficiently to withdraw the shoulder 9 from beneath the anti-creep ledge 10. Due 60 to the bearing of the forward edge of said latch member against the front wall of lifter member 2 and the engagement of shoulder 22 of member 3 with shoulder 14 of the latch member, said member 3 is blocked against further forward movement, as shown in Fig. 2 and shoulder 9 is 65 maintained beneath ledge 10.

In order to further assure against unlocking the lock under sudden coupling forces, the following construction and arrangement is preferred. Referring particularly to Fig. 2, the latch member 11 is shown with a groove 21 for engaging a curved lug 20 on the inside of the forward wall of the lock lift member 2. This groove and lug construction is preferably such that the lug lies in the groove when the member 11 is in position where it engages the shoulder 22 of member 3. The shoulder 22 may be undercut, as shown at 9', to provide a seat receiving the shoulder 14 of the latch member 11.

80 As will be apparent, the lug 20 in cooperation with the surface of the groove 21, together with the end portion 14 of member 11 in conjunction with the surface of shoulder 22, positively prevent the latch member 11 from being squeezed upwardly in the member 2. Due to the cooperation of groove 21 with lug 20, it will be seen that 85 any movement of latch 11 upwardly would necessitate that the latch 11 move in the direction of the arrow X. However, as previously noted, upon severe impact the inertia of the members 2, 3, tends to swing them in the direction opposite to 90 100 said arrow, wherefore, as is clear from Fig. 2 the latch 11 is effectively held in lowermost position. It may also be noted that a groove 21', though not essential, may be formed in the rear face of the member 11, similar to the groove 21, so that 105 the member may be put in position either way around. The undercut portion 9' of member 3 in conjunction with the groove 21' also act to prevent undesired movement of member 11 and if desired lug 20 may be omitted as shown in Fig. 4. 110

It may be noted that the top surface of the lifter member 3 connecting the shoulder 22 with the rear surface of said member is of sufficient width that the members 2, 3, cannot move through the top opening in the coupler head until they 115 have been sufficiently separated to allow them to swing forwardly with relation to each other. This can only be done by lifting the top member 2, as by means of an uncoupling rod.

120 When it is desired to raise the lock for uncoupling the top member or plug 2 is first lifted upward an amount sufficient to take up the clearance between the top of the connecting pin 7 and the upper end of the curved slot 8 in the member 3. During this movement the safety latch 11 125 is being lifted by the member 2 and by the time the clearance aforesaid is taken up the latch 11 has been lifted above the shoulder 22 and the two parts of the lifter are thereafter free to straighten out and be lifted up through the hole 130 in the top of the coupler head as shown in Fig. 3. In the latter figure the lock has been raised to lock-set position and the operator has released the uncoupling rod handle with the result that the member 2 has dropped down until the bottom 135 edge of its rear wall rests on the top end of the member 3. It will be noted also that the bottom end of the latch 11 also now rests on the top of member 3 and does not hinder any pivotal movement between said member and the member 2. 140 As soon as the lock drops to locking position, the members 2 and 3 swing rearwardly to the position of Fig. 1 and the latch 11 drops down to its working position.

145 It will thus be apparent that the present construction provides for embodying, in constructions according to my copending application above referred to, by simple changes, means for securing the additional advantages of the present construction. That is to say, the only changes which 150

need be made in accordance with the preferred form of my invention are in the lift member 2 and in the provision of latch member 11 and the pin 13.

5 The terms and expressions which I have employed are used as terms of description and not of limitation, and I have no intention, in the use of such terms and expressions, of excluding any mechanical equivalents of the features shown 10 and described or portions thereof, but recognize that various structural modifications are possible within the scope of the invention claimed.

I claim:

1. In a coupling device including a lock and 15 means to lock the lock comprising interconnected members for lifting the lock and adapted to be moved into a position for locking said lock, means carried by and movable with respect to one of said members and adapted at times to be engaged 20 by the other member for latching said other member in said locking position.

2. In a coupling device including a lock and means to lock the lock comprising interconnected 25 members for lifting the lock, means carried by and being slideable with respect to one of said members and engaging the other member for latching the other member in lock-to-the-lock position.

3. In a coupling device including a lock and 30 means to lock the lock comprising interconnected upper and lower members for lifting the lock and adapted to be moved into a position for locking said lock, means carried with the upper member for movement with respect thereto and 35 adapted to overlap a portion of the other member for latching said other member in said locking position.

4. In a car coupler, a head, a vertically movable lock, a two-part lifter connected to said lock, 40 a stop on said head, a shoulder on one of the members of said lifter cooperating with said stop for locking the lock, and a latch member carried with and movable with respect to the other member and adapted to overlap a portion of the first-named member for preventing angular movement 45 of the lifter members relative to each other in one direction.

5. In a car coupler, a head, a vertically movable lock, a two-part lifter connected to said lock, 50 a stop on said head, a shoulder on one of the members of said lifter cooperating with said stop for locking the lock, and means for latching the member against forward movement from under the stop comprising a latch member carried with and movable with respect to the other member of the lifter and having a groove in its forward side for cooperation with a lug formed on the second-named member of the lifter.

6. In a car coupler, a head, a vertically movable lock, a two-part lifter connected to said lock, 55 a stop on said head, a shoulder on one of the members of said lifter cooperating with said stop for locking the lock, and means for latching said member against movement to positions where it is out of cooperative relation with said stop, including a latch member carried with and

movable with respect to the other lifter member, a slot formed in the latch member, and a pin

carried with the second-named lifter member and engaging said slot for enabling said second-named lifter member to control said latch member.

7. In a car coupler, a head, a vertically movable lock, a two-part lifter connected to said lock, a stop on said head, a shoulder on one of the members of said lifter cooperating with said stop for locking the lock, and means for latching said member against movement to positions where it is out of cooperative relation with said stop comprising a latch member having a shoulder thereon and being vertically movable with respect to the other lifter member and carried thereby, said first-named lifter member having a shoulder for engagement by the shoulder on the latch member.

8. In a car coupler, a head, a vertically movable lock, a two-part lifter connected to said lock, a stop on said head, a portion of one of said lifter members cooperating with said stop to lock the lock, and means for latching said lifter member comprising a movable latch carried by the 100 other lifter member, said latter member having a projection formed on an inner wall thereof and said latch having a recess cooperating with said projection when the latch is in latching position.

9. In a car coupler, a head, a vertically movable lock, a two-part lifter connected to said lock, a stop on said head to the rear of said lock, a shoulder on one of the members of said lifter cooperating with said stop for locking the lock, 110 and means engageable with said member for latching the same against forward movement when said member is in locking position, said means being carried by the other member of said lifter and movable vertically with respect thereto. 115

10. In a car coupler, a head, a knuckle, a vertically movable lock for said knuckle, a two-part lifter connected to said lock, the members of said lifter being loosely connected together for assuming a certain position with respect to each 120 other during lifting of the lock and a different position with respect to each other when the lock is in knuckle locking position, one of said members having a portion underlying a ledge of the coupler head to prevent upward movement of the 125 lock when in locking position, and means comprising another member movable with respect to both said lifter members and cooperating therewith for maintaining said portion under said ledge while said lock is in locking position.

11. In a car coupler, a head, a vertically movable lock, a two-part lifter connected to said lock, a stop on said head to the rear of said lock, a shoulder on one of the members of said lifter cooperating with said stop for locking the lock, 135 and means for latching said member against forward movement when said member is in locking position, said means being carried by and being slideable with respect to the other member of said lifter.

ARTHUR J. BAZELEY.
